UNITED STATES PATENT OFFICE.

HERBERT McCORNACK, OF GLEN RIDGE, NEW JERSEY.

AIR WASHER AND CARBURETOR.

Application filed September 2, 1921. Serial No. 498,110.

This invention relates to air washers and carburetors used for supplying fuel to internal combustion engines.

The general object of my invention is to provide a new and improved air washer and carburetor which will be efficient and reliable in operation and will supply a proper mixture of washed air and fuel to the engine in connection with which the invention is used. While one of the principal novel features of the invention is the arrangement whereby air is cleansed and moistened, certain other features of my air washer and carburetor are believed by me to be useful and novel, and these also will be claimed as part of my present invention.

The invention will be understood from the following description, taken in connection with the accompanying drawings, in which

Figure 1 is a cross-sectional elevation of a carburetor embodying my invention;

Fig. 2 is a sectional plan on the line 2—2 of Fig. 1;

Fig. 3 is a sectional elevation on the line 3—3 of Fig. 2;

Fig. 4 is a sectional plan on the line 4—4 of Fig. 1;

Fig. 5 is a plan view of the lower half of the carburetor, the carbureting chamber and the parts above it being removed;

Fig. 6 is a sectional elevation on the line 6—6 of Fig. 5;

Fig. 7 is an elevation, partly in section, of a form of air cleanser and moistener embodying the invention which may be used in connection with any carburetor.

Fig. 8 is a side elevation showing the device of Fig. 8 arranged in cooperation with a carburetor; and

Fig. 9 is a sectional elevation of a portion of the slotted member through which the air is admitted in the device shown in Fig. 7.

Referring to the drawings and particularly to Figure 1, the carburetor is shown as having a central portion 11, preferably of cast metal, in which is located the fuel reservoir 12, receiving fuel through a pipe 13 leading to a source of fuel supply (not shown). The level of the fuel in the reservoir 12 is maintained substantially constant by means of a needle valve 14, of any well known form, controlled by a float 15 attached to a lever 16 which is pivoted at 17 and connected to a needle valve 14 by a ball-and-socket joint 18, as shown.

Below the central portion of the carburetor is the air cleanser and moistener, which will now be described. In the form shown, this comprises a vessel 19 formed by a cylindrical sheet metal casing 20, open at its lower end and at its upper end provided with an axial opening adapted to engage a flange 21 extending downwardly from the central casting 11. At its bottom edge, the casing 20 is adapted to fit within the flanged edge 24 of a member 25, which is tangentially slotted, as shown in Figures 1, 2 and 3. Surrounding and frictionally engaging the member 25, is a cylindrical cup 26, which contains the cleansing and moistening liquid, usually water. The cup 26, which is provided with a rib 27, which engages a groove in the member 25, extends upwardly somewhat beyond the top of flange 24, and thus provides an annular space between the upper edge of said cup and the casing 20 and above the flanged edge 24 of the slotted member 25. The air for the explosive mixture enters the carburetor downwardly through this annular space, through the outer portion of the slots 28, under the lower edge of the casing 20, and upwardly through the inner portions of the slots 28, which are covered with the cleansing and moistening liquid. Owing to the tangential arrangement of the slots 28, the passage of the air through said slots sets up a whirling motion in the cleansing and moistening liquid, which materially contributes to thorough mixing of the air and liquid and consequently to thorough cleansing and moistening of the air.

The necessary supply of liquid is fed to the cup 26 through a pipe 30 which extends upwardly through the carburetor, and at its upper end passes through a cork 31 in the bottom of a closed receptacle 32 containing the supply of liquid. As the liquid in the cup is used up, air will gradually enter at the bottom of the pipe 30 and will pass up into the reservoir 32, thereby permitting the liquid to flow from said reservoir downwardly through the pipe 30 and into the cup 26 until the bottom of the pipe 30 is again sealed by the liquid. The member 25 is provided with a hole 34 through which the dirt in the liquid settles into the cup 26; and holes 35 near the top of the member 25 provide communication between the space above and the space below the middle of the member 26. The pipe 30 serves not only

to convey the liquid to the pan 27, but also to hold together the various parts of the carburetor. At its bottom end, the pipe 30 is threaded and provided with a wing-nut 37, which screws against a perforated washer 38. Between the washer 38 and the member 25, is preferably interposed a yielding and porous packing material 39. With this construction, it will be understood that the member 25 is drawn upwardly into firm engagement with the lower edge of the casing 20 and that the latter is drawn upwardly toward the central casting.

As best shown in Figure 5, the fuel reservoir 12 is annular in form and occupies circumferentially about three-fourths of the space within the central casting 11. The remaining portion of the central casting forms an intermediate chamber 40 which communicates axially with the vessel 19 above described within which the air is cleansed and moistened. The intermediate chamber 40 is provided on its curved wall with a passage 41 of the form best shown in Figures 1, 5 and 6. This passage 41 forms a circumferential communication between the intermediate chamber 40 and the mixing chamber 42 above it. This mixing chamber 42 is formed by a sheet metal cylindrical casing 43, the lower edge of which rests within a flange 44 at the top of the central casting 11 and upon a cover 45 provided for the latter. At its top, the casing 43 is provided with an axial opening adapted to receive a flange on the conduit 47 which thus is axially connected with the carbureting chamber 42. It will be understood that the other end 48 of the conduit 47 is connected to the internal combustion engine, and that the supply of explosive mixture is controlled in the usual way by the butterfly-valve 49. It will also be observed that the pipe 30 passes through the conduit 47 and is provided above the conduit with a nut 50 which engages the conduit 47 and forces the latter and the casing 43 into engagement with one another, and also forces the casing 43 into engagement with the cover plate 45 when the wing-nut 37 is tightened.

In the particular embodiment of the invention shown, the cleansing and moistening vessel 19 and the mixing chamber are provided with heating jackets through which a portion of the hot exhaust gases from the engine may be conveyed. These jackets consist of casings 53 and 54, preferably of sheet metal, of the form best shown in Figure 1.

The fuel is introduced into the air while the latter is passing through the circumferential passage 41 leading from the intermediate chamber 40 to the carbureting chamber 42; and the arrangement whereby the fuel is conveyed to this passage will now be described. The central casting is provided with an extension 60 which may

be integral with said casting or may be formed separately and secured thereto. This extension is bored so as to form passages therein. Extending downwardly from the bottom of extension 60, is a tube 61 having a closed bottom and connected to the fuel reservoir 12 through a passage 62 extending inwardly through the extension 60 and communicating with a circumferential passage 63 formed in the outer bottom edge of the intermediate chamber 40 and communicating with the reservoir 15, these parts being best shown in Figures 1 and 6. In these passages from the reservoir 12 to the tube 61, there is either a restricted portion of fixed size or an adjustable restricted portion such as that provided by a needle-valve not shown. The fuel in the tube 61 is drawn out through a pipe 65 which extends downwardly into said tube and thus makes connection with the latter near its bottom. This pipe 65 at its upper end communicates with a passage 66, which in turn communicates with a passage 67 extending inwardly through the extension 60 and into the circumferential passage 41 through which the air passes from intermediate chamber 40 into the carbureting chamber 42. The passage 67 may contain either a restricted portion of fixed size or an adjustable restricted portion such as that provided by the needle-valve 68.

My carburetor is also provided with means for allowing air to pass from the intermediate chamber 40 directly into the mixing chamber 42 independently of the circumferential connection 41. This means may consist of a valve 75 of the form best shown in Figure 1, centrally arranged in the cover 45 of the central casting 11. As shown, the valve 75 is provided with a downwardly extending hub 76 having an inturned flanged bottom which engages with a sleeve 77 slidably arranged on the pipe 30. The sleeve 77 and the valve 75 are yieldingly held in the position shown in Figure 1 by a coiled spring 78 surrounding the pipe 30 and engaging the top of the sleeve 77. The upper end of the coiled spring 78 engages the bottom of a circular plate 80 provided with an opening through which the pipe 30 extends as shown in Figure 1. The cover 45 for the central casting is provided with vertically standing fins 81 of form best shown in Figure 4; and the plate 80 is clamped against the top of said fins by any suitable means such as screws 82 passing through plate 80 and into the cover 45. The cover 45, the plate 80 and the fins 81 thus provide means for directing the air coming through the valve 75 into the path of the fuel and air mixture entering the mixing chamber 42 through the circumferential connection 41 between that chamber and the intermediate chamber 40. It will be noted that the fins 81 are so formed and arranged that the air 130

passing through the valve 78 will be given a whirling motion in the same direction as the whirling motion imparted to the fuel and air mixture entering the mixing chamber 42. In this way, the fuel and air mixture and the additional air admitted through the valve 75 are thoroughly mixed within the mixing chamber 42.

Figures 7, 8 and 9 illustrate an air cleanser and moistener embodying the invention, adapted for use with any one of many well-known types of carburetor. In this embodiment of the invention, the vessel 85 in which the cleansing and moistening of the air takes place may have a cylindrical wall 86 of glass or any other suitable material. Glass is preferred because it permits the interior operation to be observed. At its bottom edge, the casing 86 is adapted to fit within the flanged edge 87 of a member 88 which is provided with tangential slots 90, as shown in Figures 7 and 9. The member 88 may be formed of any suitable material, and may be either molded or machined to the desired form. The liquid retaining bottom of the vessel 85 consists of a cylindrical cup 94 which extends upwardly somewhat beyond the top of the flange 87 of the member 88 and is provided with a rib 95 which frictionally engages a groove in the member 88. The cup 94 may be removed when it is necessary to clean the device or disassemble it for any reason. The top of the vessel 85 consists of a flanged cover 96 having an axially connected conduit 97 through which the moistened and cleansed air passes to the carburetor. The flanged member 96 is provided with an axial opening through which extends a pipe 98 which serves both as a feed pipe for the cleansing and moistening liquid and as a bolt or tie-rod for holding the various parts together. The pipe 98 is provided near its top with a threaded portion engaged by a nut 99 which cooperates with the top of a lug 100 on the flanged cover 96; and at its lower end the pipe 98 is threaded and engaged by a nut 101 which cooperates with a spring 102 located between said nut and the top of a recess in the bottom of the member 88, as clearly shown in Figure 7. When the various parts are assembled, as shown in Figure 7, the pressure of the spring 102 placed under compression by the nut 101 tends to hold the member 88 snugly against the bottom of the casing 86, which in turn is held in close engagement with the bottom of the flanged cover 96. If desired, packing rings 104 may be interposed between the top and bottom edges of the shell 86 and the parts with which those edges cooperate. The slotted member 88 is provided with holes 106 which connect the space below the member 88 with the space above that member. The pipe 98, which is preferably open at its bottom end, is also provided with one

or more holes 107 located just above the upper surface of the member 88. The pipe 98 at its upper end is connected through a pipe 108 to a sealed reservoir (not shown) containing the supply of cleansing and moistening liquid. Whenever the level of the liquid in the cleansing and moistening vessel 85 is below the top of the holes 107, air will enter those holes and will bubble upward through the pipes 98 and 108 to the reservoir, thereby permitting liquid to flow downward into the vessel 85 until the level rises above the holes 107. The air to be cleansed and moistened enters downwardly through the annular space between the top of the cup 94 and the outside of the casing 86, through the slots 90, under the lower edge of the casing 86 and upwardly through the inner portions of the slots 90 which are covered with the cleansing and moistening liquid. Owing to the tangential arrangement of the slots 90, the flow of air through said slots sets up a whirling motion in the cleansing and moistening liquid, which contributes to thorough mixing of the air and liquid, and consequently to thorough cleansing and moistening of the air. As the liquid in the vessel 85 is used up, air will gradually enter the pipe 98 through the holes 107 and will pass up into the reservoir, thereby permitting additional liquid to flow from the reservoir into the vessel 85. The air cleansing and moistening device which is shown in Figure 7 is shown in Figure 8 as connected through the conduits 97 and 110 with the air intake opening of the carburetor 111, of any well known form, which need not be described. In fact, the invention, in so far as it relates to an air washer, may be used in any connection in which the washing or moistening of air is desirable.

While I have shown certain constructions in which my invention may be embodied, I wish it to be understood that these details of construction may be modified in many respects without departing from the spirit of my invention as set forth in the appended claims.

I claim—

1. An air cleaner and moistener comprising a chamber for the moistening liquid, a chamber above the same in which the air is to be moistened, the walls of said upper chamber fitting within those of said lower chamber to provide an annular air passage into said upper chamber, a partition between said chambers, means on said partition forming tangential slots which extend from the periphery of said partition to within the periphery of said upper chamber for the admission of air thereto, and to set up a whirling action in said chamber, and means to maintain a body of liquid in said moistening chamber substantially filling said slots.

2. In a carburetor, the combination of a vessel within which the air is cleansed and moistened, an intermediate chamber connected with said vessel, a carbureting chamber connected with said intermediate chamber, a conduit connected with said carbureting chamber, a feed pipe for the cleansing and moistening liquid extending through
- 10 said conduit, carbureting chamber, intermediate chamber and vessel, and means co-operating with said pipe for clamping said parts in cooperative relation.

In testimony whereof I have affixed my signature to this specification.

HERBERT McCORNACK.
